UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

PHONOGRAPH RECORD.

Application filed April 20, 1923. Serial No. 633,463.

This invention particularly relates to the centering apertures with which phonograph records are provided to insure correct positioning of the records upon the record table 5 of a phonograph.

The usual practice in the molding of phonograph records is to provide the molding die with a pin for forming the centering aperture, and for giving to the centering aperture a cylindrical surface which abruptly meets the plane reproducing surface of the record. The sharp edges which are thus produced tend to become chipped from engagement with the usual spindle of the record table, and where an identifying label, which has a central aperture registering with the centering aperture of the record, is affixed to the record, the edge or wall of the central aperture in the label is generally 20 abraded by engagement with the spindle. The centering aperture then presents an unsightly appearance. In addition to the above mentioned undesirable results flowing from the present usual practice of molding phonograph records, the die itself has a tendency 25 to leave fins or other imperfections where the cylindrical spindle engaging surface of the centering aperture meets the plane reproducing surface of the record.

The main object of my invention is to provide a phonograph record having a centering aperture of improved form adapted to be engaged by the spindle of a phonograph record table without attendant injury 35 to the record or to the label which is usually affixed thereto.

Another object of my invention is to provide a phonograph record which tends to prevent engagement by the spindle of the record table with the wall of the central aperture in a label affixed to the record.

Other objects of my invention will become apparent as the detail description progresses, reference being had to the accompanying 45 drawings, wherein

Fig. 1 is an elevation of a phonograph record embodying the novel features of my invention, and

Fig. 2 is an enlarged fragmentary section 50 taken on line 2-2 of Fig. 1.

Fig. 3 is an enlarged fragmentary sectional view taken longitudinally through one wall of the centering aperture in the record.

In the drawing the reference character 55 designates in its entirety a phonograph rec-

ord of the disk type. Records of this type are molded of plastic material by dies of the type shown and described in my co-pending application Serial No. 633,462, filed under even date herewith.

While my invention may be applied to either a single-faced or a double-faced phonograph record, I prefer to show a double-faced record having two labels 11 and 12 affixed thereto to identify the sounds recorded upon plane surfaces of the record. Each of the labels 11 and 12 is preferably depressed below its associated reproducing surface as shown in Fig. 2. The labels are affixed to the record by the die in which the record is molded, the labels being properly positioned in the die before the moldable compound is placed therein.

The record 10 is provided with a centering aperture 13 of improved form which is adapted to receive the usual spindle of a rotatable record table. The centering aperture and spindle provide means for quickly and properly positioning the record upon the record table.

The centering aperture 13 has a cylindrical surface 14 of material length adapted to fit the usual spindle somewhat snugly, and chamfered to provide a plurality of frustoconical surfaces 15 and 16 which join the cylindrical surface 14 with plane surfaces of the record. It is readily understood that the blunt edges formed by the chamfered ends 15 and 16 together with the cylindrical surface 14 and the plane surfaces of the record are not easily chipped when the record is engaged by the spindle of the record table. It is also readily understood that the chamfered ends 15 and 16 aid in aligning the centering aperture 13 with the spindle.

The chamfered ends of the centering aperture not only protect the record in positioning it upon the record table, but also protect it when removing the record for the reason that care is very seldom taken to lift the record in a true vertical direction and it is more frequently tilted, and in such tilted position, the chamfered ends of the centering aperture accommodate themselves to the centering spindle and thereby prevent damage to both end edges of the centering aperture. With a single faced record, the chamfered end of the centering aperture may be at the plane face only of the record, as the liability of damage is

greater at the underside of the record than at the upper side thereof, but it will of course be understood that chamfering of both ends of the centering aperture in a single faced record has the same advantage as in a double faced record, except that a single faced record is always placed upon the record table with the plane face of the record at the underside thereof and is never inverted as in the use of a double faced record.

As shown in Fig. 2 each of the labels 11 and 12 is provided with a central aperture 18 which has its edge spaced from the cylindrical surface 14. Spacing the edges of the apertures 18 from the cylindrical surface 14 in this manner permits the plastic material of which the record is made to be molded so as to provide shoulders 19 which abut the edges of the apertures 18 and protect them from the abrasive action of the spindle.

I prefer to have portions of the surfaces of the labels 11 and 12 form portions of the frustro conical surfaces 15 and 16, but it is apparent that the edges of the apertures in the labels could be spaced any desired distance from the centering aperture 13 and yet be protected by shoulders formed upon the record. Turning the edges of the apertures inwardly is advantageous in that any imperfections in the joint between these edges of the label and the record are less noticeable than would be the case if the edges of the apertures were in plane surfaces of the records.

I am aware that changes in the form, construction and arrangement of parts may be made without departing from the spirit and without sacrificing the advantages of the invention and I reserve the right to make all such changes as fairly fall within the scope of the following claims.

I claim:

45 1. A phonographic disk record having a centering aperture and a label affixed to the disk record and having an opening registering with said aperture, the edge of the label at said opening being embedded in the body 50 of the record to prevent the wearing and damaging of said edge.

2. A phonographic disk record having a centering aperture and a label affixed to the disk record and having an opening registering with said aperture, the disk record

having a recess adjacent said aperture receiving the edge of the label at said opening, said edge lying outside of the plane of the rest of the label and within the centering aperture and thereby being protected from engagement with objects coming in contact with the outer surface of the label.

3. A phonographic disk record having a cylindrical centering aperture and a label affixed to the disk record and having an opening registering with said aperture, the disk record having a recess adjacent one end of said aperture and receiving the edge of the label at said opening, said edge lying outside of the plane of the rest of the label and within the centering aperture and thereby being protected from engagement with objects coming in contact with the outer surface of the label, a portion of the record which defines said aperture extending radially inwardly with respect to said edge to prevent engagement of said edge with the turn-table spindle which is received in said aperture.

4. A phonographic disk record having a label affixed on one side thereof, the label and the record having a centering aperture to receive a turn-table spindle, the aperture in the record being chamfered and shouldered at its end to receive the apertured edge of the label whereby said edge of the label will be protected from engagement with objects coming in contact with the surface of the label and also protected from engagement with the turn-table spindle.

5. As an article of manufacture, a phonograph record having a label affixed thereto, the record having a centering aperture a portion of the surface of which is formed by a surface of the label.

6. As an article of manufacture, a phonograph record having a label affixed thereto, the record having a centering aperture terminating at one side of the record in a frustro conical surface partially formed by a surface of the label.

7. As an article of manufacture, a phonograph record having a label affixed thereto and having a centering aperture registering with an aperture in the label, the wall of the centering aperture having a shoulder abutting and covering the wall of the aperture in the label.

JOSEPH W. BISHOP.
